ARTICLE OF MANUFACTURE AND THE
METHOD OF MAKING SAME

Albert Herman Sauer, Jr., Cincinnati, Ohio

Application December 28, 1934, Serial No. 759,539

6 Claims. (Cl. 69—21)

This invention relates to an ornamental leather thong, the method of making same and an improved wrist watch band or strap therefor.

An object of this invention is, therefore, an improved leather thong or cord which is durable and may be employed for forming wrist watch straps, ties and other purposes, particularly ornamental wherein a certain amount of utility is required.

10 Another object of the invention is the provision of an improved method for the manufacture of leather thongs which results in a thong that will withstand both perspiration and other normally destructive agents without splitting or becoming affected thereby.

15 A further object of this invention is the provision of a rolled leather thong for decorative and utilitarian purposes which has its inherent durability enhanced by a suitable strengthening element or core and in which the parts are united to resist the normal destructive elements which rendered prior thongs impractical.

20 A further object of the invention is the provision of an improved wrist watch band employing the leather thong above described in which the strength and durability of the normal leather wrist watch band is materially increased without detracting from the decorativeness and flexibility of the leather bands.

25 30 A still further object of the invention is the provision of an improved leather wrist watch band retaining all of the comforts of heretofore known leather wrist watch bands without being subject to the inherent defects thereof.

35 Other objects and advantages of the present invention should be readily apparent from the following specification taken in connection with the accompanying drawings, and it is to be understood that any modifications may be made in the 40 exact structural details there shown and described without departing from or exceeding the spirit of the invention as defined in the appended claims.

45 In the drawing:

45 Figs. 1 to 4 inclusive illustrate the several steps in the process of manufacturing the improved leather thong of this invention;

50 Fig. 5 is a plan view of a wrist watch and its strap utilizing the improved thong;

55 Fig. 6 is a perspective view showing the various elements, in proper relative positions but detached from one another, forming one section of the strap;

55 Fig. 7 is a perspective view similar to Fig. 6

showing the elements for the other section of the strap;

Fig. 8 is an enlarged sectional view taken on line 8—8 of Fig. 5 and showing the relative positions of the thongs as utilized in each strap section; and

Fig. 9 is a perspective view of a modified form of improved thong of my invention.

Throughout the several views of the drawing similar reference characters are employed to denote the same or similar parts.

In the past flexible wrist watch straps have been made employing cord, rope and leather thongs, which, however, have not withstood the usual wear and tear incident to the wrist watch strap. In prior structures the leather thongs were rolled and the ends thereof cemented to one another which cement would be deteriorated by perspiration and climatic conditions causing same to disintegrate and the ends of the thong to separate and render same unsatisfactory and frequently unfit for further use. By the present invention the said ends of the thongs are permanently connected by means not acted upon by perspiration and the like, and therefore a wrist watch strap may be provided having all of the advantages of prior leather wrist watch straps without the inherent disadvantages thereof.

The thong of the present invention is shown at the right-hand side of Fig. 4, and as there shown it will be noted is of circular cross-section and indicated by the reference numeral 10. This thong is provided throughout its length with a core 11 which is a long tough fiber cord.

As was mentioned above, the method for forming this thong is illustrated in Figs. 1 to 4 inclusive and is as follows. A flat piece of leather 12 having a length depending upon the size of the hide from which it is cut and a width to suitably encircle the core 11. As seen in Fig. 1, the core or cord 11 is laid along the longitudinal center of the leather strip 12 whereupon the strip is folded around the cord or core 11 with the longitudinal edges of the strip substantially adjacent one another. The ends of the strip 12 are then secured to one another by means of a line of stitching 13 which is disposed as close as practicable to the core or cord 11 for tightly encasing the said core or cord within the strip 12 as shown in Fig. 2.

The portion 14, Fig. 2, of the longitudinal sides of the strip 12 is then removed as closely as practicable to the line of stitching 13 which results in a semifinished product as shown in Fig. 3 bringing the now raw edge 15 of the thong adjacent the stitches 13. The cross-sectional area of the thong

is now substantially circular with, however, a short depending tongue 16 caused by the sewing machine stitches 13 which naturally cannot so closely approach the core 11 as to form a continuation of the periphery of the strap around the core as to form a part thereof.

The next and final step in the process is the swaging of the tongue 16 into the body of the thong so as to provide a truly cylindrical cross-section. This is effected by drawing the thong of Fig. 3 through an aperture 17 in a die block 18 suitably held against movement. To assist in starting the thong through the aperture 17 the end thereof may be skived or pointed as shown in dotted lines at 19 in Fig. 4. The drawing of the thong through the die block 18 upsets the tongue 16 of Fig. 3 and more or less compresses same into the body of the thong and results in a thong having a cylindrical cross-section.

20 In Fig. 9 there is shown a modification of the improved leather thong indicated by the reference numeral 10—A. This thong is made by substantially the same process just described except that it is hollow or devoid of the core piece 11. 25 In the manufacture of the thong illustrated in Fig. 9 the strip of leather is folded upon itself with a slight air space at the bend which is practically negligible whereupon the edges are sewed to one another. The excess material between the 30 stitches and the extreme ends of the strip is then removed whereupon the thong is passed through the die block 18. The passing of the modified thong through the die block effects a uniform cross-sectional area throughout the length there- 35 of and reduces the air space of the tube to a negligible quantity.

From the foregoing it will now be appreciated that there has been provided a leather thong of circular cross-section in which no cement or other agent has been employed which can be attacked by perspiration, climatic conditions or the like. It will further be noted that this thong has its ends permanently united and will withstand normal wear and usage to the limit of each of 45 the various elements therein.

The improved wrist watch band illustrated in Fig. 5 comprises band sections 20 and 21 attached in any usual or desirable manner to a wrist watch 22. Specifically, the strap section 20, illustrated in Fig. 6, comprises an attachment piece 23 folded upon itself and provided with a line of stitching 24 to form an eye 25 through which the pin bar 26 passes. The free ends of the piece 23 are skived to a relatively thin edge and receive between them a plurality of short sections 27 of the improved cored thong 10. The sections 27 and the free ends 28 and 29 of the attaching piece 23 are united to one another by a line of stitching 30. The lateral edges of the free ends of the piece 23 may be tapered from the eye 25 to the ends thereof depending upon the design to be achieved or the width of the band as compared to the width of the watch or the spacing of the lugs projecting from the watch.

65 The other ends of the sections 27 are received between the ends 31 and 32 of the buckle-holding piece 33. The buckle-holding piece 33 similar to the attaching piece 23 is a piece of leather folded on itself to provide an eye 34 for the buckle 35, said eye 34 being formed by a line of stitching 36 just behind the buckle. The ends 31 and 32 of the buckle piece 33 are secured to the thong sections 27 by a line of stitching 37 in the same manner as the said sections and the attaching piece 23 are secured to one another.

The section 21 of the strap, similar to section 20, has a watch-attaching piece 38, similar in all respects to the attaching piece 23, from which project thong sections 39. The free ends of the thong sections 39 are received between the ends 40 and 41 of the strap tongue 42 which cooperates with the buckle 35. The tongue 42 is formed of a single piece of leather folded on itself and having the free ends 40 and 41 attached to the thong sections 39 by means of a row of stitches 10 43. The tongue 42 is provided with a plurality of perforations 44 adapted to receive the buckle tongue 45 as is usual practice.

From the foregoing it will be noted that there has been provided an all-leather wrist watch strap 15 utilizing leather attaching parts and leather strap sections each of which are formed without the use of cement, paste or the like which would be subject to perspiration, dampness or other climatic conditions. It will further be noted that 20 the finished strap is very artistic and pleasing in appearance without in the least sacrificing the utility and durability of the various elements.

What is claimed is:

1. The process of producing a leather thong 25 consisting in folding a strip of leather entirely around a flexible core, uniting the ends of the leather to one another by stitching as closely as practicable to the core, removing the surplus material from the strip adjacent the stitching, and 30 passing said thong through a die block to cause the raw edge as effected by the trimming step to be embedded in the body of the thong and the resultant thong having a uniform cross-section corresponding to the die block. 35

2. The process of producing a leather thong consisting in folding a strip of leather upon itself with the edges thereof in direct contact, uniting the edges of said strip to one another by means of stitching, removing the surplus material between said stitching and edges thereof, and passing the thong through a die block to reduce same to a uniform cross-section. 40

3. The process of producing a leather thong for decorative and utilitarian purposes consisting 45 in folding a strip of leather about a flexible core with the edges thereof in direct contact, uniting the ends of said leather by stitching same to one another at a point adjacent the core, and reducing the assembly to a uniform cross-section from 50 end to end.

4. A thong for decorative and utilitarian purposes comprising a leather strip folded on itself and with the free edges thereof in direct contact and secured to one another and said thong having 55 the free edges of the strip, adjacent the securing means, embedded in the thong to provide a uniform cross-section from end to end.

5. A flexible leather thong comprising a leather strip having its longitudinal edges in direct contact, means for permanently uniting the said longitudinal edges of the strip, said strip having the free edges thereof, beyond the uniting means, embedded in the strip to form a tube, and a 60 flexible core encased by said tube. 65

6. A flexible leather thong comprising a leather strip having its longitudinal edges in direct contact, and means for permanently uniting the said longitudinal edges of the strip, and said strip having the free edges thereof, beyond the uniting means, embedded in the strip to provide the thong with a uniform cross-section. 70
